ABSTRACT

The present invention relates to an improved quick disconnect arrangement for attaching linkages to the baseplate of a trolley of an overhead conveyor.

OVERHEAD CONVEYOR TROLLEY PLATES

The present invention is an improvement on the conveyor trolleys described and claimed in U.S. Pat. Nos. 2,884,116 and 3,190,236. The improvement resides specifically in the area of the connection between the linkage and the base plate of the trolley.

It is an object of the present invention to provide a connection between an overhead trolley linkage and base plate which requires no crimping or other distortion of any component.

It is another object of the present invention to provide a connection between an overhead trolley linkage and base plate which can be assembled or disassembled by the aid of a simple readily available tool such as an end wrench or hand pliers.

It is a further object of the present invention to provide a connection between an overhead trolley linkage and base plate which reinforces the strength of the base plate.

Other objects and advantages will become apparent upon recourse to the following specification and drawings in which:

FIG. 1 is a side view of a trolley of the present invention;

FIG. 2 is a top view of the trolley of FIG. 1;

FIG. 3 is a side view of one of the two plates which comprises a trolley base plate;

FIG. 4 is a top view of the plate of FIG. 3, and

FIG. 5 is a side view of a keeper plate of the present invention.

The trolleys 10 of the present invention are generally the same as the trolleys of the above-identified patents in that they comprise two identical base plates 12, two vertical wheels 14 attached to the base plate sections 12 by a bolting assembly comprising a bolt 24 and spacers 25, and a horizontal wheel 16. Also, in both cases the trolleys are connected together by linkages 20.

In the present invention each of the base plate sections 12 is formed with a boot-shaped slot 18 on each side of the hole 19 for the bolting assembly 24 having a rounded toe opening 30.

Keeper plates 22 overlie the plates 12 as shown in FIG. 2. Each keeper plate 22 has an opening 26 which also receives

the bolting assembly 24 and two openings 28 which overlie the toe openings 30 in the plates 12 when assembled.

To assemble a trolley with linkages a wheel 16 and two plate sections 12 are assembled as described in said above-identified patents and an eye of a linkage 20 is placed into each slot 18 and moved down into the toe opening 28. A keeper plate 22 is then positioned on each side of the two plate sections 12 with each opening 28 engaging a linkage eye 20 and a bolting assembly 24 is then bolted in position as shown in FIGS. 1 and 2 and the trolley is complete.

In assembled condition the keeper plates 22 prevent the linkages 20 from riding up out of the slots 18 and thus retain the linkages 20 in operative position at all times. This entire assembly was performed with any convenient tool such as a wrench or pair of pliers and no crimping, hammering or other position disruptive type of operation was required.

Also in assembled condition the keeper plates 22 both stiffen and strengthen the base plate sections 12 and add to its tensile strength between the two linkages 20.

20 The present invention makes it possible to remove a trolley from and replace a new trolley into a conveyor system by just the removal of one bolt with a standard tool such as a wrench.

The foregoing specification is to be considered as descriptive and not limitative as many changes and modifications can be made in the physical embodiment of the present invention without departing from the spirit and scope of the invention.

The invention having been disclosed, what is claimed is:

1. A conveyor trolley comprising a base plate, wheels, a wheel shaft carried by said base plate for fastening said wheels thereto, said base plate having two vertical slots therein terminating in an edge thereof, a pair of trolley connector linkages each having an eye end positioned with the eye inserted into one of said slots, a keeper plate positioned to prevent movement of said connector eyes out of said slots and also fastened to said base plate by said shaft.

2. A conveyor trolley as specified in claim 1 in which said keeper plate extends substantially across and connects the opposite sides of said base plate to strengthen said base plate.
